M. M. WATSON

WINDOW CURTAIN SUPPORT

Filed June 2, 1923

UNITED STATES PATENT OFFICE.

MARGARET M. WATSON, OF NEW YORK, N. Y.

WINDOW-CURTAIN SUPPORT.

Application filed June 2, 1923. Serial No. 642,923.

To all whom it may concern:

Be it known that I, MARGARET M. WATSON, a citizen of Canada, and a resident of the city of New York, in the county of New

5 York and State of New York, have invented certain new and useful Improvements in Window-Curtain Supports, of which the following is a full, clear, and exact description.

The invention relates to certain improvements in curtain supports for windows generally, and has for its principal object to provide for a support adapted to sustain the depending end portions of lace curtains or similar window draperies above the sash 10 opening of a window, when the sash is raised for ventilation purposes, and whereby the curtains or draperies will be prevented from being mussed, crushed or otherwise damaged, such as has heretofore occurred in known 15 methods of securing the curtain or drapery ends clear of a window opening for the obtaining of the full and unobstructed ventilating effects therefrom and against being blown about by the inrush of air there- 20 through.

Another object of the invention is to provide for a curtain support of the character mentioned, and one of a comparatively simple and inexpensive construction and arrangement, such as will be easy to install and operate as well as durable in use, and which will be capable of vertical adjustment to effect a raising and lowering of the supported curtain or drapery ends in the manner herein- 25 before indicated for the same.

With the forgoing and other equally important objects in view, the invention resides in the certain new and useful construction and arrangement as will be hereinafter more 40 fully described, set forth in the appended claims and illustrated in the accompanying drawing, in which:—

Figure 1 is an elevation of a window showing a preferred embodiment of the invention as applied thereto.

Figure 2 is a vertical section taken on the line 2—2 of Figure 1,

Figure 3 is a vertical section through the curtain support per se, showing a modified 50 form of the elevating cord.

Figure 4 is a fragmentary bottom plan view of the vertically movable portion or member of the support.

Referring to the drawing, the improved 55 curtain support as shown therein comprises an upper stationary member 10 formed of

telescopically engaged tube sections 11 and 12, and a lower relatively movable member 13 formed of similarly engaged tube sections 14 and 15.

The upper member 10 is to be adjusted lengthwise to the full width of the sash receiving opening of a window casing, and has the opposite outer ends of its telescopic sections 11 and 12 outturned to provide 60 flanges 16 to abut the inner faces of the vertical side portions *a* of the window casing and for the fastening of the same thereto by means of screws or the like 17, while the lower movable member 13 is to be adjusted 65 to a length slightly less than the width of the window opening for free movement vertically between the opposite side portions *a* of the window casing. Immediately inward of the opposite outer ends of the sections 70 14 and 15, of the movable member 13, are formed aligned pairs of upper and lower openings or eyelets 18, 18', and 19, 19', respectively, which, when the lower member 13 is disposed in operative relation below the 75 upper stationary member 10, are aligned with similar openings or eyelets 20 formed in the lower sides of the sections 11 and 12 of the latter.

The lower movable member 13 is to be 80 supported from the upper stationary member 10 by means of a flexible element 21, such as a suitable length of cord or wire, suitably looped between the members for the purpose, and which has a central or intermediate portion passing through the tube sections 14 and 15, of the lower member 10, with its opposite end portions passing outwardly of the upper of the openings or eyelets 18 and 19 therein, and from thence to and inwardly 85 of the openings or eyelets 20 in the sections 11 and 12, of the upper member 10, through the latter and then outwardly of the openings or eyelets 20, from which they depend and pass through the pairs of aligned openings or eyelets 18, 18', and 19, 19', all in a manner that the lower member 13 will be 90 supported in parallel relation with and below the upper member 10. The free depending ends of the flexible element 21 are preferably 95 provided with counter-weights 22, so that the lower movable member 13 will be sustained in any desired position with respect to the upper member 10, when not in active use.

In the use of the curtain support as thus 100 constructed and arranged, and with the

window to which the same is secured provided with lace curtains or the like *b* at the inner side thereof, when it is desired to open the lower sash of a window for ventilating purposes, the lower depending ends of the lace curtains *b* will be looped in an upward direction and laid over the lower member 13, so that by now grasping the weighted end portions of the flexible element 21 and pulling downward on the same, the lower member 13 will be raised to a desired height to support the looped ends of the lace curtains *b* clear of the sash opening.

To sustain the movable member 13 in any of its elevated positions, when the curtain ends are supported thereon, the depending ends of the flexible element 21 may be wound around or otherwise engaged with suitable cleats or the like 23 secured at the opposite sides *a*, of the window casing, for the purpose, or, if desired, the openings or eyelets 18' and 19' at the lower sides of the sections 14 and 15, of the lower member 13, may be formed with tapered offset slots or openings 18'' and 19'', respectively, for the wedging of the free ends of the flexible element into engagement therewith, for such purpose.

In the event of the lower member 13 being disposed in an elevated position, by the action of the counter-weight 22 when the member is not in active use, the same is to be moved to a lowered position for the placing of the depending curtain ends thereon by a pull cord or the like 25 depending from an eyelet 24 secured at the under side of the tube section 15, which eyelet 24 is preferably positioned at the approximate center of the member 13 whereby to equalize the downward pull on the flexible element 21 between the lower and upper members 13 and 10.

To prevent the possible slipping of the looped curtain ends from engaged position on the lower member 13, the upper sides of the tube sections 14 and 15 thereof, are provided with a series of frictional members 26 for the purpose.

From the foregoing, it will be readily apparent that, while a preferred embodiment of the curtain support has been described and illustrated herein in specific terms and details of construction and arrangement, various changes in and modifications of the same may be resorted to without departing from the spirit of the invention, or the scope of the claims appended hereto.

As shown in Fig. 3, one of the extensions of the element 21 may be dispensed with and providing thereby means whereby the sections 14 and 15 may be elevated by pulling upon one end of the element 21. This requires that the element 21 shall be anchored firmly to the sections 11 or 12 as shown at 27 in said Figure 3. Other modifications may be employed for varying the working position of the tubes 14 and 15.

Having thus fully described the invention, what is claimed, is:—

1. A curtain or drapery support for windows comprising a telescopic tubular stationary member, a telescopic tubular movable member disposed below said stationary member, and an adjustable suspension means extending between and through said members.

2. A curtain or drapery support for windows comprising a stationary tubular member, a movable tubular member disposed below said stationary member, and a flexible suspension element looped between the opposite end portions of said members and passing through the bores thereof, said suspension means being adjustable for effecting the raising and lowering movements of said movable member.

3. A curtain or drapery support for windows comprising a telescopic stationary member of tubular formation, a telescopic movable member of a tubular formation disposed below said stationary member, a flexible suspension element looped between said members adjacent the opposite ends thereof and having its free ends depending below said movable member, weights secured to the opposite free ends of said flexible element for counter-balancing said movable member in any of its inactive positions of use, and means for securing the free end portions of said flexible element when the movable member is operatively disposed.

4. A curtain or drapery support for windows comprising a stationary tubular member of telescopic sections, a movable member of similar formation disposed below said stationary member, a suspension cord passing through the opposite ends of said members and forming a continuous loop through and between said members, and cord securing means carried by said movable member.

MARGARET M. WATSON.
